UNITED STATES PATENT OFFICE

130,741

DESIGN FOR A HOOD

Ida Brenner, New York, N. Y.

Application May 7, 1941, Serial No. 100,825

Term of patent 7 years

To all whom it may concern:

Be it known that I, Ida Brenner, a citizen of the United States of America and a resident of New York, in the county and State of New York, have invented a new, original, and ornamental Design for Hoods, of which the following is a specification, reference being had to the accompanying drawing forming a part hereof.

I claim:

The ornamental design for a hood, as shown.

IDA BRENNER.
